(57) **CLAIM**

The ornamental design for a fishing reel, as shown and described.

DESCRIPTION

FIG. 1 is a rear perspective view of a fishing reel that includes a fishing reel portion in accordance with my new design;

FIG. 2 is a first side elevational view of the fishing reel illustrated in FIG. 1 that includes the fishing reel portion; FIG. 3 is a second side elevational view of the fishing reel illustrated in FIG. 1 that includes the fishing reel portion but in which the fishing reel portion is completely hidden from sight;

FIG. 4 is a top plan view of the fishing reel illustrated in FIG. 1 that includes the fishing reel portion;

FIG. 5 is a bottom plan view of the fishing reel illustrated in FIG. 1 that includes the fishing reel portion but in which the fishing reel portion is completely hidden from sight;

FIG. 6 is a rear elevational view of the fishing reel illustrated in FIG. 1 that includes the fishing reel portion;

FIG. 7 is a front elevational view of the fishing reel illustrated in FIG. 1 that includes the fishing reel portion but in which the fishing reel portion is completely hidden from sight;

FIG. 8 is an enlarged perspective view of a portion of the fishing reel illustrated in FIG. 1 that includes the fishing reel portion;

FIG. 9 is an enlarged side elevational view of the fishing reel illustrated in FIG. 1 that includes the fishing reel portion; and,

FIG. 10 is an enlarged side elevational view of another embodiment of the fishing reel, which is identical to the fishing reel illustrated in FIGS. 1 to 8, except that a boundary is shown in dot-dash broken lines.

In the drawings, the broken line illustration of the environmental structure (the remaining structure of the fishing reel) in the drawings is not part of the claimed design. In other
